ABSTRACT OF THE DISCLOSURE

After the top skived edge of a shoe upper has been turned and cemented to form a folded-back top border, about half an inch of the fold at the ends of the upper which are to be stitched together to form the back seam are opened up to facilitate the stitching of the back seam, thus forming small end flaps. When the back seam has been stitched, cement is applied to these flaps and the herein described machine is employed to fold the flaps back again and press them in place.

This invention relates to a special pressing machine for a particular purpose, namely, to finish the top edge 25 of a shoe upper at the back seam thereof.

When an upper has been cut to shape, the top edge is skived, cemented, and doubled back to form a smooth bead. This is usually done by a machine designed for the purpose. The ends of the upper must then be stitched together to form the back seam. To facilitate this stitching operation, about half an inch of the bead at each end is opened up, forming small flaps at the ends of the top bead of the upper. When the ends of the upper have been stitched together to form the back seam, the flaps must be doubled back again to form a smooth, continuous bead at the back of the upper. For this purpose cement is again applied to the flaps which are then doubled back and pressed to form a uniform bead with the rest of the top of the upper. The herein described machine is designed to enable an operator to perform this operation quickly and effectively to provide a uniform product.

For a more complete understanding of the invention, reference may be had to the following description thereof and to the drawings, of which:

FIGURE 1 is a perspective view of a machine embodying the invention;

FIGURE 2 is a front elevation of the novel parts of the machine;

FIGURE 3 is a side elevation of the same;

FIGURE 4 is a plan view of the same as indicated by the lines IV—IV of FIGURE 2;

FIGURE 5 is a plan view of the anvil, showing part of an upper initially applied thereto;

FIGURE 6 is a similar view showing the upper moved toward the back-stop;

FIGURE 7 is a section on the line VII—VII of FIGURE 6;

FIGURE 8 is a fragmentary sectional view of the same;

FIGURE 9 is a plan view of the upper in its final position on the machine; and

FIGURE 10 is a fragmentary sectional view of the same.

The machine illustrated on the drawings is of the bench type being supported by a pillar 20 having a base plate 22 secured to a table 24 or other suitable support. A conventional pneumatic or hydraulic press 26 is pro-

2

vided with a pressure-regulating valve 28 and dial gauge 30. Valves for operating the press are not shown.

Secured to the pillar 20 is an anvil having a conical body 32 with a short cylindrical base 34, next to which is a cylindrical back-stop 36. Extending in from the apex of the body 32 is a slot 38 in which is fitted a plate 40. As indicated in FIGURES 1 and 7, the upper portion of the plate 40 projects out from the surface of the body 32 forming a rib the upper edge 42 of which is curved and terminates a short distance from the cylindrical base portion 34 of the body 32. The plate is adjustably secured in position by a screw 44 which extends through a slot 46 in the plate. Thus the height of the rib above the conical surface of the body can be adjusted as desired.

Above the base 34 of the anvil body is an arcuate presser foot 50 which is pivotally attached to a piston rod 52 projecting down from the press 26. The presser foot 50 is of metal with a soft liner 54 of vulcanized rubber or an equivalent.

The machine is operated for the specific purpose of completing the bead at the top of a shoe upper adjacent to the back seam after the back seam has been stitched. The bead along the top of the upper is usually made before the back seam is stitched. To do a good job of stitching, about half an inch of the bead at each of the ends of the upper to be joined by the seam is opened up, forming small flaps 60 (FIGURE 5) on each side of the back seam 62. After a suitable cement has been applied to the under faces of the flaps 60 by a brush or other suitable means, the upper is manually applied to the anvil so that the back seam 62 rides on the upper edge of the plate 40 with the flaps riding over the end of the rib. The upper is then moved toward the back-stop 36 with the result that the flaps 60 are curled under as indicated in FIGURE 8, completing the bead along the top edge of the upper. The upper is pushed along further until the bead is on the base 34 of the anvil and against the back-stop 36, whereupon the presser foot 50 is pressed down on the portion of the bead which is on the base 34 by operation of a convenient control valve (not shown). This flattens and smooths that portion of the bead, making it uniform with the rest of the bead.

I claim:

1. A machine for finishing a bead along the top edge 45 of a shoe upper adjacent to the back seam thereof, comprising a conical anvil having a short cylindrical base, a rib projecting from the conical surface of the anvil and extending longitudinally thereof, a semi-circular presser foot adapted to fit on said cylindrical base, and means 50 supporting said anvil with its axis horizontal and said presser foot vertically movable above said base.

2. A machine as claimed in claim 1, and a plate adjustably secured within said anvil, said plate having a marginal portion projecting from the conical surface of the anvil 55 and constituting said rib.

3. A machine as claimed in claim 2, and a cylindrical back-stop next to said base.
